UNITED STATES PATENT OFFICE.

EDWIN R. PROBERT, OF COVINGTON, KENTUCKY, ASSIGNOR TO THE MOESCHL-EDWARDS CORRUGATING COMPANY, OF COVINGTON, KENTUCKY, A CORPORATION OF KENTUCKY.

SHEET-METAL ROOFING.

1,144,725.

Specification of Letters Patent. Patented June 29, 1915.

Application filed March 13, 1915. Serial No. 14,260.

To all whom it may concern:

Be it known that I, EDWIN R. PROBERT, a citizen of the United States of America, and a resident of Covington, in the county of 5 Kenton and State of Kentucky, have invented a certain new and useful Improvement in Sheet-Metal Roofing, of which the following is a specification.

This invention relates to joints for sheet-10 metal roofing and especially to the particular form or type seen in prior Letters-Patent No. 1,123,921 granted to me January 5, 1915, in which a lower-crimp having a concaved or guttered apex is overlapped by an oppositely-sloping crimp and the fastening-nails 15 are driven through the apex of the lapped joint into the sheathing beneath.

The object of the present invention is to preferably provide within its scope firm and 20 rigid supports for the sloped capping or overlapping member of the joint that serve to stiffen and strengthen the joint and will not give way under the force of the blows required in capping and in nailing the joint, 25 nor the weight of those walking on the roof when in use.

The device is capable of considerable modification, as will fully appear in the drawings forming a part hereof, and in the 30 description of the details that hereinafter follow.

In the accompanying sheet of drawings, that illustrate the device in somewhat exaggerated form, Figure 1 is an end elevation 35 of the preferred form of roof-joint embodying my invention herein and somewhat ornamental in appearance or effect; Fig. 2, a similar view, but of a modified, plain form; Fig. 3, a similar view, but of still another 40 modification that is only partly ornamental; and—Fig. 4, a view similar to Fig. 2 but of a modification whose capping-member has a true, pointed apex and is not ornamental, a fastening-nail being shown in position driven through the capped-joint into 45 the sectioned sheathing below.

1 indicates a roofing-sheet and 2 another contiguous roofing-sheet, both to be laid and joined together in the usual method of covering suitable sheathing.

3 indicates an upright shallow bead or corrugation running parallel to the longitudinal lapped-edge of sheet 1; 4, a contiguous, parallel corrugation somewhat

higher than the one 3; 5, a horizontal foot 55 or base extending from corrugation 4; 6, a slightly slanting limb or upright-member leading from the base 5 having a companion oppositely-slanting limb or upright-member 7, both limbs 6 and 7 being straight ones 60 and duly spaced apart at their upper convergent ends by means of a downwardly-curved or guttered ligament or truncated apex-member 8; and 9, a foot or base which is a companion to the base 5 and extends 65 laterally from the lower edge of the limb or upright-member 7, with an upwardly and outwardly sloping flange-member 10 along its outer edge.

11 indicates an upright shallow bead or 70 corrugation running parallel to the overlapping longitudinal edge of the sheet 2 that is joined to sheet 1, such bead 11 being a companion one to the bead 3 in the sheet 1 and coinciding with it in purpose and appearance for harmonious effect both mechanically and ornamentally.

12 is a sloping member extending upwardly from the outer lower edge of the bead 11 and having at its upper edge a bead 80 13 that has at its outer lower edge a downwardly-curved or channel member 14, the bead 13 and channel-member 14 forming a slanting S-formation that extends into another sloping vertical member 15 whose upper edge, in turn, has a horizontal straight or flat apex connecting-member 16 to unite 85 it with a vertical member 17, a companion to the sloping member 12 but oppositely sloping at the same angle. A slanting S-formation 90 is made along the lower edge of the member 17, and is composed of a downwardly-curved or channel member 18 and a bead 19, similar to the S-formation along the lower edge of the vertical member 15 95 and the outer edge of the bead 19 extends downwardly and slopes outwardly to form a fender 20 to correspond to the like formation or member 12 along the bead-formation 11. Thus the parts or elements are made in 100

like or corresponding parts that impart a harmonious and somewhat ornamental effect to the joint when it is laid, with the members 12, 13, 14, 15, 16, 17, 18, 19 and 20 105 duly overlapping or overtopping the members 10, 9, 7, 8, 6, 5 and 4, and providing ample ventilating and drainage chambers or passages 21 and 22 beneath the two sloping

S-shape formations in the capping or upper joint-member. The downwardly-curved apex-member 8 of the capped or lower joint-member provides an upper ventilating chamber beneath the capping joint-member.

In the use of my preferred form of joint seen in Fig. 1 any possible seepage beneath the outer fender 20 is shunted so as to drop from the underside of the channel-member 18 into the bottom of the first large drain-chamber 21, but should it be at all possible for any seepage whatever to get to the top of the sloping upright-member 6 it will pass off along the guttered apex-member 8, and should it be even further possible for any seepage to go still farther along the sloping upright-member 15 it will drop off the underside of the channel-member 14 into the second large drain-chamber 22. Any seepage along the sloping upright-member 7 must, of course, pass on downward into the bottom of chamber 22 and drain off along the same. The chances of any seepage getting beyond the barrier 18 and the first drain-chamber 21 are, of course, extremely remote, but the subsequent barriers impart or afford still greater security and efficiency in the joint against leakage into the sheathing beneath.

The pair of upright-members 6 and 7 combine to form a stiff and rigid support for the upper or capping-member of the joint and certainly give great strength to the joint as well as to form walls or partitions that result in the ample ventilating and drain chambers 21 and 22, and they are made slightly sloping or spreading away from each other downwardly so as to facilitate the manufacture of the joint and adapt it to close packing or nesting with others in piles or stacks, free to be easily parted when required.

The nails used are of any ordinary form, as seen at 23 in Fig. 4, and the usual soft washers 24 accompany, beneath the heads thereof, to prevent leakage.

The various elements of structure thus far described are of such form as to adapt the joint to be economically and easily made without much bending or shaping of the metal and with materially fewer dies and less die-work. There is no material increase, if any, in the use of material in the formation of this joint and it may be made either ornamental to a greater or less extent as in Figs. 1 and 3, or perfectly plain, as in the remaining views.

It will be readily seen that there are but few lapped or connecting surfaces of any degree whatever in the joint, thereby reducing the chances of seepage or leakage from capillary attraction to a minimum.

The bead or corrugation 3 serves as a material guard or barrier to the entrance of water by wind or otherwise beneath the

lower edge of the fender-end 20 of the capping-member of the joint that is of importance and advantageous.

In Fig. 2, I have shown a modified form that omits the beads 3, 11, 13 and 19 and the channels 14 and 18, thus providing an inverted V-shaped lapping-member having continuous straight sides 25 and 26, and a flat or truncated apex, the latter the same however, as in Fig. 1. The drain-chambers 21 and 22 of this form are certainly ample and most effective against seepage.

In Fig. 3, I have shown the same structure as in Fig. 1 excepting that the slanting S-shape formations in the sloping sides of the upper or lapping member of the joint are omitted and said sloping-sides 25 and 26 made plain, as in Fig. 2.

In Fig. 4, I have shown a plain inverted V-shape capping-member with straight sloping sides 25 and 26, the same as in Fig. 2, and without the beads 3, 11 and 19 of Fig. 1, but it has a true, pointed apex, and the capped-member is the same as in Fig. 2. The chamber within the top of the joint is of larger area in this form than in the other truncated forms, and it requires less material and die-work to produce this form of joint too, but the seepage-barriers are not so numerous and the effect not quite so great and satisfactory as in the other forms.

It will be observed, especially in Fig. 1, that the various elements of both the lapping and lapped members of the joint herein are made in corresponding pairs, including thereunder the upright limbs 6 and 7; the feet or bases 5 and 9; the flange 10 and the upright bead or corrugation 4; the beads or corrugations 3 and 11; the upper slanting-members 15 and 17; the beads 13 and 19; the channels 14 and 18; and the lower slanting-members 12 and 20, all of which are easily made and assembled for packing or use, and a most symmetrical effect follows when the joint is laid.

I claim:

1. A lap-joint for sheet-metal roofing comprising a lower or lapped member having a pair of corresponding, slightly spreading limbs or uprights, a concaved or guttered apex-ligament connecting the upper edges of said limbs, lateral feet or bases projecting from said limbs, an outwardly-flaring flange extended upwardly from one of said feet, an inverted V-shape crimp projecting from the other of said feet and forming part of one of the sheets to be joined, and an upper or lapping member having spreading or outwardly-sloping sides whose meeting point or apex vertically aligns with said guttered apex-ligament of the lower or lapped member and whose said sloping-sides cover the lower-member so that a large ventilating and drain chamber or passage is provided between each of them and the ad-

jacent limbs or uprights of the lapped member.

2. A lap-joint for sheet-metal roofing comprising a lower or lapped member having a pair of corresponding, slightly spreading limbs or uprights, a concaved or guttered apex-ligament connecting the upper edges of said limbs, lateral feet or bases projecting from said limbs, an outwardly-flaring flange extending upwardly from one of said feet, an inverted V-shape crimp projecting from the other of said feet and thence extending into a roofing-sheet to be joined to a companion-sheet, and an upper or lapping member having spreading or outwardly-sloping sides whose upper meeting-

point or apex vertically alines with said guttered apex-ligament of the lapped-member and each of whose said sloping sides has a slanting or inclined S-shape crimp therein somewhat elevated above its lower edge and one or more longitudinal upright beads or corrugations made in the roofing-sheet one of them adjacent the outer edge of one sloping side of the lapping-member and the other one adjacent the said inverted V-shape crimp in the lapped-member. 20 25

EDWIN R. PROBERT.
